UNITED STATES PATENT OFFICE.

FREDERIC KETTLER, OF MILWAUKEE, WISCONSIN.

FORCE-PUMP.

Specification of Letters Patent No. 24,877, dated July 26, 1859.

To all whom it may concern:

Be it known that I, FREDERIC KETTLER, of the city and county of Milwaukee and State of Wisconsin, have invented a new and Original Machinery of a Force-Pump to Supply an Engine with Water, and do hereby declare that the following is a full and exact description of the same.

This engine has thirty-two pumps, when 10 it is of a common size and will throw out every minute seven hundred gallons of water. Through the operation and construction of the machinery the water will be forced more regularly and in a greater quantity through the pipes of the engine.

Figure 1 represents a side elevation of the engine and Fig. 2 the plan.

Similar letters refer to like parts.

a is a hollow space or vessel. This vessel 20 has a movable cover which will be fastened air tight to sustain the pressure of the water if the machinery is in operation.

A are two cylinders which are fastened on the right and left below the back part 25 of the vessel *a*. The pipes *S* are fastened to the cylinders and are intended to draw the water out the well and to force it by means of valves through the pipe *t* into the vessel *a* as is indicated by arrowheads.

30 Figs. 3, 4 and 5 are different views which show the working of the valves *C* and levers *F*, *g*, *h*, and are drawn on a larger scale. Through the center of the cylinders *A* an axis *k* moves itself freely by means of cranks

35 *R*. *B* is a rotary cylinder which has on each end a flange *Q* and is fastened to this axis *k*. *C* are the valves which work exactly between the flanges *Q* and close to the surface of this cylinder *B*. Every valve has two 40 journals *V* which pass through the flanges.

On the outer sides of the flanges the levers *F* are represented,—they are fastened on the journals *V* and serve to open the valves *C* by means of the lever *g*. The levers *h* are fastened within the stationary cylinders *A* 45 and are intended to shut the valves *C*. The levers *g* are also fastened in the center of this cylinder and are intended to open the valves *C*. If the cylinder *B* receives now its rotary motion by the cranks *R* the levers 50 *F* come first in contact with the levers *g* and cause to open the valves *C*—and when afterward with the levers *h* they will be shut again. This vessel *a* is filled with water to the top of the above placed pipe *Z* by 55 means of two sets of pumps, in Figs. 3, 4 and 5 described. Within this vessel a number of pumps of a smaller size as described in Figs. 3, 4 and 5 are in working and force their water through smaller pipes into the 60 tube *m* which is secured below the vessel *a*.

U is the discharge pipe which is fastened to the tube *m*.

The toothed wheels *O* are working freely in the frame *p* by means of cranks—and 65 the toothed wheel *M* which is fastened on the axis *k*, is connected with those in *O* by means of a chain *D*. Those wheels and the cranks *K* are used to produce the rotary motion of the machinery in the cylinder *A*. 70

What I claim as my invention is—

The combination and arrangement of a force pump as herein described, for the purpose set forth.

FREDERIC KETTLER.
